UNITED STATES PATENT OFFICE

OSCAR J. WATTS, OF KENSINGTON, KANSAS

MERRY-GO-ROUND

Application filed January 25, 1928. Serial No. 249,392.

This invention relates to a merry-go-round especially adapted for use at playgrounds, school yards and the like, and has for one of its objects to provide a device of this character which shall be adapted to seat a comparatively large number of children, which shall be adapted to be operated by the children seated thereon and which shall be adapted to be operated without danger to the children seated thereon and to those standing within the vicinity of the same.

A further object of the invention is to provide a merry-go-round of the character stated which shall be simple and practically indestructible and which shall be adapted to be manufactured and sold at a comparatively low cost.

A still further object of the invention is to provide a merry-go-round which shall embody a center post, endless seats surrounding the post, a seat supporting frame, and means for supporting the frame on the post for rotation upon the same at the least possible friction.

With the foregoing and other objects in view, the nature of which will appear as the description proceeds, the invention consists in the construction, combination and arrangement of parts hereinafter fully described and claimed, and illustrated in the accompanying drawings, wherein:

Figure 1 is a view in side elevation of the merry-go-round.

Figure 2 is a top plan view of the merry-go-round.

Figure 3 is a sectional view taken on the vertical plane indicated by the line 3—3 of Figure 1.

Figure 4 is a sectional view taken on the vertical plane indicated by the line 4—4 of Figure 2, and

Figure 5 is a similar view taken on a vertical plane indicated by the line 5—5 of Figure 2.

The merry-go-round comprises a center post 1 which is hollow and cylindrical and has its lower end portion fixed in a concrete base 2 embedded in the ground. A hollow bearing boxing 3 for a vertical spindle 4 is supported within the upper end portion of

the post 1 by an annular flange 5, which extends outwardly from the upper end of the boxing and rests upon the upper end of the post. The upper end wall 6 of the boxing 3 is provided at its axial center with an opening 7 for the reception of the spindle 4. The spindle 4 rests at its lower end upon anti-friction balls 8 which are mounted in a recess 9 formed in the upper side of the lower end wall 10 of the boxing 3. The boxing 3 is larger diametrically than the spindle 4 to adapt it to contain a lubricant for the spindle and anti-friction balls 8. The spindle 4 extends above the boxing 3, and its upper end portion 11 is reduced and screw-threaded.

A collar 12 is rotatably supported on the post 1 by an annular shoulder 13. The collar 12 is located at or near the horizontal center of the post 1, and the shoulder 13 may be formed integrally with or made separately and secured to the post. The collar 12 is provided with radially extending coupling members 14 of substantially semi-cylindrical formation. A cap 15 rests upon the spindle 4, and it is secured to the spindle by a nut 16. It is provided in its lower side with a recess 17 which is larger diametrically than and receives the upper end portion of the post 1. The cap 15 is provided with downwardly and outwardly extending coupling members 18 of semi-cylindrical formation.

Arms 19 extend radially from the sleeve 12, and they are secured to the coupling members 14 by bolts 20. Braces 21 extend from the cap 15 to the upper sides of the arms 19. The braces 21 are secured at their upper ends to the coupling members 18 by bolts 22. The lower ends of the braces 21 are horizontally disposed as shown at 23 and are secured to the arms 19 by bolts 24. Vertical bars or standards 25 are secured to the arms 19 and to the braces 21 by bolts 26. A standard 25 is provided for each pair of the arms 19 and braces 21. The standards 25 reinforce the arms 19 and braces 21 and they extend above the braces to adapt them to support a hand bar and back rest 27. The hand bar and back rest 27 is of annular formation, and it is secured to the outer sides of the standards 25 by bolts 28. The standards 25 also reinforce

the connections between the arms 19 and braces 21.

The arms 19 extend outwardly beyond the lower ends of the braces 21, and secured to 5 and between the outer ends thereof are boards 29 which constitute the seats of the device. The seat boards 29 are secured to the arms 19 by plates 30 which are secured to the upper and lower sides of the seat boards by bolts 31 and which contact with the upper and 10 lower sides of the arms.

In practice, the children occupying the seats 29 may rest against and hold on to the bar 27 and operate the device with their feet.

15 As the seat 29 is continuous and surrounds the post 1, there is no danger of the children on the seats or those standing near the device being injured. All parts of the device, with the exception of the base 2 and the seats 29, 20 are made from metal. The arms 19, braces 21, standards 25 and hand bar and back rest 27 are hollow, and these parts may be secured together and the arms and braces may be secured to the coupling members 14 and 18 by 25 rivets instead of bolts or by any other suitable means. The plates 30 may also be secured in place by rivets or any other suitable means. The device requires little or no attention to maintain it in a high state of efficiency, the lubricant in the boxing 3 will last 30 for several years, and any wear in the spindle 4, balls 8 and boxing walls 6 and 10 may be compensated for adjusting the nut 16.

From the foregoing description taken in 35 connection with the accompanying drawings, the advantages of the construction will be readily apparent to those skilled in the art to which the invention appertains. While I have described a device which I now consider 40 to the best embodiment of the invention, I desire to have it understood that the device shown is merely illustrative, and that such changes may be made when desired as are within the scope of the invention as claimed.

45 What is claimed is:—

1. A merry-go-round comprising a post, a sleeve and a cap rotatably mounted on the post, arms secured to and extending outwardly from the sleeve, braces connecting the cap 50 and the arms, standards secured to the arms and braces and extending above the latter, seat boards secured to the arms, and an annular member secured to the upper ends of the standards.

55 2. In a merry-go-round, a post, a boxing carried by the post and provided in its bottom wall with a recess and in its top wall with an opening, anti-friction balls mounted in the recess, a spindle resting upon the balls 60 and passing upwardly through the opening, a cap secured to the spindle and having a recess therein receiving the upper end of the post, and coupling members on the cap for securing braces thereto.

65 3. In a merry-go-round, a tubular post, a

boxing recessed into the upper end portion of the post and provided with a flange resting upon the upper end of the post, a spindle carried by the boxing, a cap secured to the spindle and having a recess therein receiving the upper end of the post, and coupling members 70 on the cap for securing braces thereto.

In testimony whereof I affix my signature.

OSCAR J. WATTS.
